CLAIM

I claim the ornamental design for a post connecting spandrel, as shown and described.

DESCRIPTION

FIG. 1 shows a top, front, right side perspective view of the first embodiment of the post connecting spandrel.

FIG. 2 shows a right side elevation view thereof.

FIG. 3 shows a top plan view thereof.

FIG. 4 shows a front elevation view thereof.

FIG. 5 shows a rear elevation view thereof.

FIG. 6 shows a left side elevation view thereof.

FIG. 7 shows a bottom plan view thereof.

FIG. 8 shows a sectional view taken along lines 8-8 of FIG. 7.

FIG. 9 shows a top, front, right side perspective view of the second embodiment of the post connecting spandrel.

FIG. 10 shows a right side elevation view thereof.

FIG. 11 shows a top plan view thereof.

FIG. 12 shows a front elevation view thereof.

FIG. 13 shows a rear elevation view thereof.

FIG. 14 shows a left side elevation view thereof.

FIG. 15 shows a bottom plan view thereof.

FIG. 16 shows a sectional view taken along lines 16-16 of FIG. 15.

FIG. 17 shows an environmental perspective view of the post connecting spandrel in its state of use of FIGS. 1 through 8; and,

FIG. 18 shows an environmental perspective view of the post connecting spandrel in its state of use of FIGS. 9 through 16.

The broken lines rendered in FIGS. 17 and 18 illustrate the environment of the claimed design and forms no part thereof.

1 Claim, 8 Drawing Sheets
